UNITED STATES PATENT OFFICE

2,680,799

ELECTRICAL HEATING UNIT

Butler Ames, Boston, Mass.

Application November 13, 1952, Serial No. 320,202

3 Claims. (Cl. 219—19)

1

This invention pertains to electrical heating units and more especially to a unit for use in cooking apparatus or the like wherein a source of intense radiant energy is desired. Such a unit is useful, for example, in a cooker of the kind disclosed in the patent to Ames No. 2,581,343 dated January 8, 1952. While particularly useful in cooking apparatus, the improved unit is also of value as a heat source in other devices, for example in room heaters of the kind disclosed in the patent to Ames No. 2,555,668 dated June 5, 1951.

Among objects of the invention are to provide a heater unit comprising improved means for supporting the heat-emitting resistance coils. A further object is to provide an improved heater unit wherein a thin but rigid disk carries spaced brackets for supporting a plurality of independent resistance coils in a plane substantially parallel to the face of the disk and spaced from the latter. A further object is to provide a heater unit wherein a rigid disk of heat-resistant material, for example stainless steel, and which also acts as a reflector, supports insulated resistance coils and carries rigid terminal posts designed for telescopic engagement with current-supplying sockets. Other and further objects and advantages of the invention will be pointed out in the following more detailed description and by reference to the accompanying drawings wherein:

Fig. 1 is a plan view of a heater unit embodying the present invention;

Fig. 2 is a bottom view of the unit of Fig. 1;

Fig. 3 is a diametrical section substantially on the line 3—3 of Fig. 1, omitting all but two of the coil-supporting brackets, and to larger scale, showing details of construction;

Fig. 4 is a side elevation, to still larger scale, to one of the coil-supporting brackets of the unit; and

Fig. 5 is a perspective view of an insulating grommet.

Referring to the drawings, the numeral 1 designates a supporting plate, here shown as a disk of sheet material. This disk should be rigid and capable of withstanding the heat radiations to which it is subjected without buckling or oxidizing. Stainless steel is suitable for the purpose and when of a thickness of the order of $\frac{1}{16}$ inch provides all of the requisite stiffness and rigidity. However, while stainless steel is well suited for this purpose it is contemplated that other materials having the proper physical characteristics may be employed. Whatever material is selected should desirably be capable of acting as a reflec-

2

tor to reflect heat radiations, which impinge upon it, back toward the source.

This supporting plate or disk carries a plurality of resistance elements which, when traversed by the electric current, admit the desired radiations. As here illustrated two such resistance elements 2 and 3 are shown, each of these elements consisting of a simple coil of resistance wire without any interior core, the two resistance elements 2 and 3 being arranged so as to form concentric circles lying in the same plane spaced from the plane of the disk 1. The terminals 3^a and 3^b of the outer coil 3 are connected to terminal posts 4 and 5 respectively which pass through openings in the disk 1, with insulation, (Fig. 3) for example mica washers 6 and 7, interposed between the posts and disk, the posts being fixed to the disk in any suitable manner and projecting from the opposite side of the disk from that at which the elements 2 and 3 are located. Preferably these terminal posts are longitudinally split and designed for telescopic engagement with current carrying sockets of conventional form, thus permitting the disk with the resistance coils to be installed as a unit in the apparatus of which it is intended to become a part and to be removed as a unit merely by pulling the terminal posts out of their sockets. The terminals 8 and 9 of the inner coil 2 are connected, one to the post 5 and the other to a third terminal post 10 similar to the posts 4 and 5. Desirably the lead ends of the coils, running from the coils proper to the respective terminal posts, are protected by suitable insulation, for example a series of insulating beads B strung on the lead wires.

The resistance coils 2 and 3 are supported by rigid brackets 11 fixed to the disk 1. As illustrated in Fig. 4, each of these brackets comprises two inverted, substantially U-shaped, members desirably formed from a stiff metallic wire which is capable of withstanding the heat to which it is exposed in use. The outer of these two U-shaped members (Fig. 4) comprises the parallel legs 12 and 13 united by the substantially horizontal bridging member 14, the legs merging with this bridging member 14 at bends 25 and 26 of substantially 90° of arc. The free ends of the legs 12 and 13 are screw threaded, as shown at 15 and 16.

The other of the U-shaped members comprises the parallel legs 19 and 20 and the bridging member 21, but this bridging member is bent to provide the inwardly directed curved portions 23 and 24, these curved portions cooperating with the

bends 25 and 26 of the outer U-shaped member to provide spaces 27 and 28 partially bounded by the inner and outer curves 23 and 25 and 24 and 26 respectively. The legs 19 and 20 of the inner U-shaped member are shorter than the legs 12 and 13 of the outer U-shaped member so that when the two members are assembled, as shown at Fig. 4, with the inner member nested within the outer member and with all four legs lying in the same plane, the lower ends 32 and 33 of the legs of the inner member are located substantially at the upper ends of the screw threaded portions 15 and 16 of the legs 12 and 13, while the central portion 21 of the inner U-shaped member contacts the underside of the bridge member 14 of the outer U-shaped member.

Each bracket carries two insulating grommets 29 (Fig. 5) of porcelain or the like, each grommet having a tubular barrel portion 30 and radial flanges 31 at its opposite ends.

In assembling the parts, the barrel portions of two grommets are first placed within the bends 25 and 26 respectively of the outer U-shaped member, the inner U-shaped member is then slid upwardly in nested relation to the outer U-shaped member until its bends 23 and 24 contact the barrel 30 of the grommet, and then the parts 21 and 14 are permanently united by welding at the point 22. The legs of the inner and outer U-shaped members may also be united by welding, if desired, although this is not usually necessary.

Having prepared brackets as just above described, with their insulating grommets 29 clamped in place in the spaces 27 and 28, these brackets are then mounted on the supporting disk or plate 21 and fixedly secured thereto. For this purpose the disk 1 is provided with two series of circumferentially spaced holes, a hole of the inner series lying in the same radial plane of the disk as a corresponding one of the other series, these holes being of a diameter to permit passage of the screw threaded ends 15 and 16 of the legs 12 and 13 of the brackets. The holes of each series are uniformly spaced apart. As here illustrated there are sixteen of the brackets, but it should be understood that the number of brackets may be varied in accordance with the size of the disk and as other circumstances may warrant.

Each bracket is mounted on the disk with its screw threaded ends 15 and 16 passing through a corresponding pair of holes in the disk and then nuts 17 and 18 (Fig. 2) are threaded onto the parts 15 and 16 at the opposite side of the disk from the resistance coils, thus pulling the bracket downwardly until the ends 32 and 33 of the legs 19 and 20 contact the face of the disk, these ends constituting limiting stops. After all of the brackets have been mounted on the disks and their nuts tightened, the resistance coils 2 and 3 are threaded through the barrels of the grommets, the coil 2 passing through the grommets at the inner corners of the brackets and the coil 3 passing through the grommets at the outer corners of the brackets, and then the lead ends of the coils are connected to the terminal posts, as above described.

With this arrangement the resistance coils are very firmly supported in a definite plane parallel to the disk and in such a way that they do not tend to sag during use. As already noted, these coils are without any central core and since they are fully exposed throughout their entire peripheries, intermediate the grommets of adjacent

brackets, they are very effective for emitting intense heat radiations.

Although the resistance coils are thus held very rigidly in position, the entire device is light in weight and easy to handle and readily installed or removed from the apparatus of which it is a part. It should also be noted that because of the mode of mounting the resistance coils it is a very simple matter to replace one or another of these coils if, after a prolonged period of use it should burn out, since it is not necessary to remove the brackets from the disk nor to connect the coils to the brackets other than by threading them through the grommets.

While the brackets are here shown as designed to hold insulating grommets for two coils, it is obvious that a single coil may be supported by the same type of bracket, if desired, and it is also obvious that by simple modification of the shape of the bracket it may be possible to support additional resistance coils in the same plane as the coils 2 and 3.

While a desirable embodiment of the invention has been illustrated by way of example it is to be understood that the invention is broadly inclusive of any and all modifications falling within the scope of the appended claims.

I claim:

1. In combination in a heating unit, a support, and resistance supporting brackets carried by the support, each of said brackets comprising a pair of approximately U-shaped members each having substantially parallel legs and a bridging portion, the legs of the two members being in the same plane, said members being nested one within the other with their legs in mutual engagement, the legs of the outer member being longer than and projecting beyond the legs of the inner member, said projecting ends being screw threaded, the bridging portions of the outer and inner members being so shaped as collectively to form spaced openings, tubular insulators each having a barrel portion which fits snugly within one of the respective openings in the bracket, and means so uniting the inner and outer U-shaped members as firmly to clamp the insulators in place.

2. A heating unit according to claim 1 wherein the support has spaced holes through which the screw threaded ends of the outer U-shaped members project, the ends of the inner U-shaped members engaging one face of the support and constituting stops, and nuts engaging the screw threaded ends of the legs of the outer members and which engage the opposite face of the support.

3. A heating unit according to claim 1, wherein the bridge pieces of the U-shaped members deviate symmetrically from a point of mutual engagement substantially at their mid length, laterally to the place of mutual engagement of their legs.
